UNITED STATES PATENT OFFICE.

ALFRED E. HOLMES, OF CHICAGO, ILLINOIS.

SAFETY-CAN.

1,011,198.

Specification of Letters Patent. Patented Dec. 12, 1911.

Application filed May 27, 1911. Serial No. 629,797.

To all whom it may concern:

Be it known that I, ALFRED E. HOLMES, a citizen of the United States, residing at Chicago, in the county of Cook and State of Illinois, have invented a certain new and useful Improvement in Safety-Cans, of which the following is a specification.

This invention relates to safety cans. In the particular embodiment of the device it 10 will be described as used for garbage or as a garbage can. Its object is to provide a cover which will ordinarily automatically close itself when left alone and which will automatically lock itself in closed position so 15 that the can cannot be opened accidentally or otherwise, except by a person of sufficient intelligence to operate the unlatching device.

The invention consists in a garbage can provided with a hinged cover, a spring device 20 for normally closing the cover and a latch releasable from outside the can which will automatically lock the cover in closed position except when unlatched by the hand of the operator.

25 In the drawings, Figure 1 is a side view of a garbage can equipped with the device of this invention. Fig. 2 is a side view looking at it from the left hand side of Fig. 1. Fig. 3 is a detail view of the hinge and 30 spring for closing the cover. Fig. 4 is a detailed perspective view of a latch hook stamped from one piece of metal.

In illustrating this invention in its preferred form an ordinary garbage can 10 is 35 provided, the same having at one side secured thereto by any suitable means a metallic hinge bracket 12 in which is a pivot screw 14 on which the lifting handle strap 16 is hinged, as shown. Rigidly secured to 40 the underside of this handle strap 16 is a cover 18 of ordinary construction adapted to close the can.

Extending from bracket 12 is a horizontal lug 20 to which is secured by rivets 22 45 or other suitable means a spring 24 bent in such a shape that, as shown, its end 26 engages the cover handle 16 and thus tends to close the cover 18 upon the garbage can and hold it in closed position. This spring 24 50 is of such strength and so proportioned that the cover may be swung on the pivot 14 upward from the position in Fig. 1 to a position in which the cover 18 is practically vertical and the interior of the can is, there- 55 fore, readily accessible. Movement beyond this point is checked by the engagement of

handle 16 with lug 20. Pivoted at 28 upon depending portion 30 of the handle 16 is a lever member 32 comprising a handle portion 34 adapted to be engaged by the fingers 60 or hand of the operator and a latch portion 36 having a latch jaw 38 adapted to engage a pin 40 carried by bracket lugs 42 upon the side of the can. This jaw 38 is, as shown, formed by bending from the sides of the 65 part 36 the two flaps or leaves 38^a to the position shown in Fig. 4.

Extending from the member 32 and below the pivot 28 is a projecting lug 44 adapted to be engaged by the member 36, as shown 70 in Fig. 1, so as to prevent the latch 38 from swinging too far to the right when in unlatched position, thereby preventing ready latching of the device. A spring 46 is provided upon the underside of the member 34 75 in engagement with the member 30 tending to normally hold the latch 38 in engagement with the pin 40.

In the operation of the device the can cover and latching device are normally in 80 the position shown in Fig. 1, in which position the can is closed and latched. When it is desired to place any article in the can or to remove articles already in the can therefrom the operator presses upon handle 34, 85 thus rotating the latch lever in a clockwise direction about the pivot 28 and causing latch member 38 to disengage from the pin 40. As soon as this occurs the operator is at liberty to pull up upon the handle 16, 90 and thus rotate the entire cover about pivot 14 against the action of spring 24 to a position where the articles in question can be either inserted or removed from the can. As soon as this is done the operator lets go 95 of handle 16 and spring 24 automatically closes the device, latch member 38 clicking over pin 40 into latched position, where it is held, as shown, by the spring 46. It will be noticed that the latch member and handle 100 32 are so located and shaped that merely tipping the can on its side will have no effect to unlatch the device. In other words, the device will automatically latch itself and stay latched under any ordinary conditions 105 which can occur through the can being tipped over by the wind or by a mischievous animal, while, on the other hand, it is readily operable by anyone understanding the use of the latch 32 which is so simple 110 that it can be manipulated by even a small child who has been properly instructed.

The end of handle 16 which engages hinge 14 is in rubbing contact with the inner faces 50 of the side walls of bracket 12 with the result that the cover 18 rotates in a fixed vertical plane and the latch 38 always engages member 40 instead of swinging to one side or the other, as would be the case if side play in the hinge was not thus prevented.

The claim is:—

- 10 In a device of the class described, the combination of a receptacle 10, a cover 18 therefor, a handle 16 secured to the cover and having a pivotal connection at one side with a bracket 12 secured upon the receptacle, a rod 40 carried by said bracket a spring 24 carried by the bracket and engaging the cover 16 normally tending to hold the cover in closed position, a bracket 42 upon the side of the receptacle a latch lever

32 having a latch member 38 adapted to 20 engage rod 40, and a handle member 34 bent from a vertical position to a position in proximity to the handle 16, and a spring 46 between the handle 16 and the lever handle 34 adapted to normally hold the latch in 25 locked position upon the member 40, and a lug 44 carried by the cover adapted to prevent successive movement of the latching member, all of the parts being arranged and disposed substantially as shown and described for the purposes set forth.

In witness whereof, I have hereunto subscribed my name in the presence of two witnesses.

ALFRED E. HOLMES.
